UNITED STATES PATENT OFFICE.

JAMES MCSWEENEY, OF CRETE, WEST VIRGINIA.

FLOW.

1,210,338.

Specification of Letters Patent.

Patented Dec. 26, 1916.

Application filed September 27, 1916. Serial No. 122,413.

To all whom it may concern:

Be it known that I, JAMES MCSWEENEY, a citizen of the United States, residing at Crete, in the county of Wayne, State of West Virginia, have invented a new and useful Plow; and I do hereby declare the following to be a full, clear, and exact description of the invention, such as will enable others skilled in the art to which it app-
10 pertains to make and use the same.

This invention relates to an improved plow, and an object of the invention is to improve and render more efficient and practical the form of plow illustrated, set forth, 15 and claimed in the patent issued May 16, 1916, Patent Number 1,183,138, to James McSweeney.

A further object of the invention is to simplify the means for holding a cutter 20 member in the plow beam.

A further object of the invention is the provision of a plow beam consisting of opposite sides having a filler plate between the sides substantially midway the ends of the 25 sides, and an arch standard between the rear portions of the sides, between the forward part of which arch standard and a filler block, the shank of a cutter member is securely clamped by means of a wedge, there 30 being means coöperating with a pivoted plate, to draw the wedge upwardly between the filler block and the filler plate.

In practical fields, the details of construction may necessitate alterations falling 35 within the scope of what is claimed.

The invention comprises further features and combination of parts, as hereinafter set forth, shown in the drawings, and claimed.

In the drawings:—Figure 1 is a view in 40 side elevation of the improved plow, constructed in accordance with the invention. Fig. 2 is a view partly in side elevation and partly in section of a plow. Fig. 3 is a sectional view on line 3—3 of Fig. 1.

Referring more especially to the drawings, 1 designates a metallic plow beam consisting of opposite or opposing elongated plates 2 and 3, the forward ends of which are welded together or otherwise secured as 45 shown at 4, and passing through the secured ends of said plates is a bolt 5, on which a suitable clevis 6 is pivoted, whereby a suitable evener or equalizer, not shown, may be attached. Arranged between said plates 2 and 3 substantially midway their ends is a 50 filler plate 7, secured in place by the bolts

8 and 9. Secured between the rear portions by means of the bolts 10, 11 and 12, is an arch brace 13, the forward portion of which is provided with a vertical, flat edge 14, 60 constituting an abutment. Also secured adjacent the outer faces of the elongated plates 2 and 3 near their rear ends, by means of the bolt 11, are the opposing sides 16 of the standard 17, which may be adjusted 65 pivotally upon said bolt 11.

The lower portion of the arched brace 13 is provided with a plurality of apertures 18, through any one of which a bolt 19 (which extends transversely of the standard 17) 70 may extend, whereby the standard may be held in adjusted positions.

A plow blade or shovel 20 is provided, and which is secured to the lower part of the standard by means of the bolt 21, which 75 extends through the blade or shovel downwardly and rearwardly between the two sides (which are integrally connected at their lower ends, as shown at 22) of the standard, and through a plate 23, and is pro- 80 vided with a nut 24, for securing the parts together. The rear edges of the opposing sides of the standard are provided with notches 25, which may be engaged by the teeth 26 upon the lower edge of the plate 23. 85 It is to be noted that the plow blade or shovel may be adjusted substantially in a vertical direction, by loosening the nut 24, and adjusting the plate 23. The plate 23 is provided upon its upper and lower edges 90 with lugs 27, which extend between the sides of the standard, to prevent the plate from turning. The teeth of the plate 23 engaging said notches also prevent the plate 23 from turning. 95

Passing through the opposing plates 2 and 3 substantially intermediate the rear edge of the filler plate 7 and the vertical flat edge 14 of the arched brace is a bolt 28, which also passes through an elongated slot 100 29 of the filler block 30, the rear edge of which is provided with teeth 31 while its forward edge 32 is inclined upwardly and forwardly. Arranged between the teeth 31 and the vertical flat edge 14 of the arched 105 brace is the shank 33 of the cutter 34, which in side elevation is tapering and extends downwardly and forwardly and is provided with a forward cutting edge 35, while the shank 33 extends vertically. In side elevation of the plow, the cutter 34 is at right angles to the plow blade or shovel, and is 110

disposed a trifle in advance of the plow blade or shovel. The cutter is so arranged with relation to the plow blade or shovel, that the shank 33 of said blade cannot be removed, until the plow blade or shovel is partly loosened and thrown to one side.

Arranged between the forward inclined edge 32 of the filler block and the rear edge of the filler plate 7 is a wedge 38, the upper end of which is provided with a reduced threaded extension 39.

The upper part of the arched brace has an extension 40, to which is pivoted by means of a bolt 41, the opposite sides 42 of the plate 43. The forward end of the plate 43 has an aperture or opening 44. This plate 43 is so shaped and pivoted on the upper extension of the arch brace, that said plate may be thrown down in engagement with the upper edges of the elongated opposing side plates 2 and 3 of the plow beam, whereby the threaded extension 39 may extend through the opening or aperture 44, and so that the upper ends of the filler block 30 and the shank 33 of the cutter will extend between the sides of the plate 43. The filler block 30 has a shoulder 46 which is immediately under the plate 43. A nut 47 is threaded to the extension 39, to hold the plate 43 in position, and constituting means to be adjusted, whereby the wedge 38 may be drawn upwardly, so as to coöperate between the filler plate and the filler block, to force the filler block rearwardly causing its teeth to bind against the forward edge of the shank 33, and clamp the shank between the edge 14 of the arched brace and said filler block.

Connected to the plow beam by the bolt 8 are the lower forward ends of the bars 49, which may terminate in suitable handles, not shown, but similar to the handles in the aforesaid patent. The bars 49 are connected by the transverse rod 50, and furthermore, the handle bars 49 are braced relative 45 to the plow beam by the straps 51, which are secured at their lower ends to the outer faces of the standard by the means of the bolt 11. The upper ends of said straps are secured at 52 to the handle bars.

50 The invention having been set forth, what is claimed as new and useful, is:—

1. In a plow, the combination of a plow beam consisting of opposing elongated side plates and an arched brace secured between the rear portions of said side plates and provided with an upwardly protruding extension and having a forward vertically disposed flat edge, of a filler plate secured be-

tween said opposing side plates of the beam substantially midway the ends of the beam, thereby affording a space between the filler plate and forward vertical edge of said brace, a filler block arranged substantially intermediate the ends of said space and having teeth on its rear edge, a cutter having a shank arranged between the toothed edge of the filler block and the forward vertical edge of the brace, a wedge between the filler block and filler plate to force the filler block against the shank of the cutter, to clamp the cutter shank in place, and means for drawing the wedge upwardly to cause the clamping action of the filler block on the shank.

2. In a plow, the combination of a plow beam consisting of opposing elongated side plates and an arched brace secured between the rear portions of said side plates and provided with an upwardly protruding extension and having a forward vertically disposed flat edge, of a filler plate secured between said opposing side plates of the beam substantially midway the ends of the beam, thereby affording a space between the filler plate and forward vertical edge of said brace, a filler block arranged substantially intermediate the ends of said space and having teeth on its rear edge, a cutter having a shank arranged between the toothed edge of the filler block and the forward vertical edge of the brace, a wedge between the filler block and filler plate to force the filler block against the shank of the cutter, to clamp the cutter shank in place, and means for drawing the wedge upwardly to cause the clamping action of the filler block on the shank; said means comprising a reduced extension on the upper end of the wedge, a slotted plate pivoted on the extension of the brace and having an aperture in its free end to receive the reduced extension of the wedge, and a nut threaded on the reduced extension to hold the plate in place and draw the wedge upwardly, a bolt extending through the filler block and the elongated side plates of the beam, said filler block having an elongated slot through which said last named bolt may extend, whereby the filler block may move toward the cutter shank.

In testimony whereof I have signed my name to this specification in the presence of two subscribing witnesses.

JAMES McSWEENEY.
